APPARATUS FOR SIMULTANEOUSLY PRODUCING MOVING PICTURES AND REPRODUCING SOUND PICTURES

Earl I. Sponable, New York, N. Y., assignor, by mesne assignments, to Movietone News, Inc., New York, N. Y., a corporation of New York

Original application March 29, 1927, Serial No. 179,214. Divided and this application October 10, 1931, Serial No. 568,142

9 Claims. (Cl. 88—24)

This invention relates to certain new and useful improvements in apparatus for the production of moving pictures and the simultaneous synchronized reproduction of a record corresponding to sound waves, and is a division of my co-pending application Serial No. 179,214 filed March 29, 1927.

The main object of the invention resides in the production of moving pictures simultaneously with the reproduction of sound waves from a photographic record of light waves corresponding to sound waves, and in which the reproduced sound will actually issue from the picture.

Heretofore it has been customary and practically necessary to dispose the sound reproducing device or devices at one side of or above or below the screen upon which the moving picture is projected, with the result that the sound did not come directly from the picture, and I have discovered that by the use of a special screen in combination with the other portions of the apparatus, it is possible to produce a structure and carry out a method by which simultaneously with the production of the moving picture the sound waves corresponding to the picture are actually projected through the picture, whereby a more natural and effective result is produced.

I have produced an apparatus of this character and have carried out the method successfully.

In the drawings:—

Figure 1 is a diagrammatic illustration of an embodiment of this invention.

Figures 2 and 3 are copies of photomicrographs of a sample of baronet silk.

Referring to the drawings, the moving picture screen 1 must have a coefficient of reflection sufficient to produce a good picture, and the screen must be of a character such that it will not permit the passage of light rays projected upon it. However, I have produced an apparatus including a screen having the required coefficient of reflection and the required imperviousness to light rays, which in addition is sufficiently porous to permit the substantially undamped passage of sound waves, whereby the sound producing devices can be disposed directly behind the screen, and the sound waves applicable to the picture actually projected through the picture without the absorption of any substantial amount of sound.

The material of which screen 1 is made may

have substantially the constructional characteristics of baronet silk. In order to obtain a more definite understanding of the exact structure of this material, photomicrographs of the same are shown in Figures 2 and 3. The material is generally formed of a cotton base with a front surface of silk or one of its imitations to provide a good light reflecting surface. In Figure 3, the cotton threads are indicated at 18 and the silk threads running at right angles thereto are indicated at 20. In order to present a silky front surface, threads 20 alternately pass over eight and under one cotton thread. The adjoining silk threads are not made to pass under the same cotton thread but one removed four threads to either side so as to form a staggered weave. This staggering provides openings 19 extending from front to rear of the material at varying inclinations to the flat surface thereof, which allows the sound to pass through freely but reflects substantially all of the projected light.

The apparatus as shown comprises the screen 1 and a suitable moving picture projector 2 suitably positioned for projecting light rays constituting the picture upon the screen.

In addition, there is provided a wall 5 having a narrow elongated slot 7 therein preferably corresponding substantially in area to the slot through which the sound picture was produced. The film 3 is adapted to move past the slot 7, preferably in close relation with the slot, and light rays from a suitable source, indicated at 6, are projected through the slot upon the film and pass through the sound record upon a light reactive resistance or a photo-electric cell illustrated at 8.

This photo-electric cell is connected in a circuit including any number of stages of amplification, a single stage being here illustrated, altho preferably a number of stages are used. This stage of amplification includes an electroionic device 14 of the three-electrode type, and including a filament 21, grid 22 and plate 23.

A suitable means is provided for heating the filament as for instance, a circuit including battery 13. The grid 22 and filament 21 are connected in circuit with the photo-electric cell 8, such circuit including a source of potential, as battery 12. Preferably, a potentiometer 10 and a resistance 9 are connected in shunt with said cir-

100

cuit across the filament and the grid. Potentiometer 10 is connected in shunt with a suitable source of potential as battery 11 whereby the desired potential may be maintained upon the grid for producing the most effective result.

The filament 21 and plate 23 are connected in circuit with a suitable source of potential, as battery 15, and in this case with the primary 24 of a transformer 16, the secondary 25 of which is connected in circuit with one or more translating devices 17 in the form of loud speakers disposed directly behind the screen 1, i. e. upon the opposite side of the screen from the projector 2.

Any number of translating devices 17 may be utilized and their form may be widely varied, and although two are here illustrated, I have used four with satisfactory results.

Instead of the secondary 25 of the transformer, any suitable number of stages of amplification 20 may be inserted at this point. The screen 1, as heretofore described, must be substantially impervious to light rays and must have a co-efficient of reflection sufficient to reproduce a good picture and in addition, must have openings or 25 pores of sufficient number and size to permit the passage of sound waves in substantially undamped condition.

These pores or openings may be disposed in the material which I have selected for the screen at 30 varying inclinations to the surface thereof, or other conditions of structure may assist, not herein possible to describe, but I have found that the material known as baronet silk has all of the characteristics required for accomplishing the 35 objects of this invention.

However, it may be that various other materials will be found having the same or substantially the same characteristics or perhaps improved characteristics, and for that reason I do 40 not desire to restrict myself to any particular material, but only to the fact that the structure utilized shall include a screen having the necessary co-efficient of reflection, the necessary imperviousness to light in combination with the 45 additional features that the screen permits the passage of sound waves in substantially undamped condition.

I claim:

1. A moving picture screen adapted for co-ordinated sound transmission, composed of a 50 single thickness of woven textile fabric having a front light reflecting surface to receive projected pictures and provided with interstices therethrough in number and size sufficient to permit passage of sound waves therethrough of appropriate volume without blurring, while at the same time preserving the light reflecting properties of such surface sufficiently to constitute an efficient screen, the walls of said interstices being disposed at varying inclinations to the surface of the screen, so as to prevent any detrimental back reflection therefrom.

2. A moving picture screen adapted for co-ordinated sound transmission composed solely of 65 a single thickness of woven textile fabric having a front light-reflecting surface to receive projected pictures and provided with small openings therethrough in number and size and arrangement sufficient to permit passage of sound waves therethrough of appropriate volume without blurring, while at the same time, preserving the light-reflecting properties of such surface sufficiently to constitute an efficient screen, the 70 walls of said openings extending from front to 75

rear of the screen and being so arranged as to prevent detrimental back reflection therefrom.

3. A moving picture screen adapted for co-ordinated sound transmission composed solely of a single thickness of woven textile fabric having 80 openings extending from front to rear of the screen sufficient in number and size to allow sound waves to pass through substantially unimpeded and undistorted but substantially impervious to light rays and retaining the light reflecting properties sufficiently to constitute an efficient screen.

4. A moving picture screen substantially impervious to light rays and having sufficient light reflecting properties to constitute an efficient projection screen adapted for co-ordinate sound transmission comprising a single thickness of woven textile fabric having openings extending from front to rear of the screen sufficient in 90 number and size to allow sound waves to pass through substantially unimpeded and undistorted.

5. A moving-picture screen adapted for co-ordinated sound transmission, composed solely of a single-thickness woven textile-fabric screen 100 having a front light-reflecting surface to receive the projected picture and provided with openings therethrough in number and size sufficient to permit passage of sound-waves therethrough of appropriate volume without blurring, while at 105 the same time preserving the light-reflecting properties of such surface sufficiently to constitute an efficient screen for the presentation of the pictures, the walls of said openings being made up of rounded surfaces of said woven 110 fabric.

6. A moving-picture screen adapted for co-ordinated sound transmission, composed solely of a single-thickness woven textile-fabric screen having a front light-reflecting surface to receive 115 the projected picture and provided with rectangularly shaped openings therethrough in number and size sufficient to permit passage of sound-waves therethrough of appropriate volume without blurring, while at the same time 120 preserving the light-reflecting properties of such surface sufficiently to constitute an efficient screen for the presentation of the pictures, the walls of said openings being made up of rounded surfaces of said woven fabric.

7. A moving-picture screen adapted for co-ordinated sound transmission, composed solely of a single-thickness woven textile-fabric screen having a front light-reflecting surface to receive the projected picture and provided with 130 openings therethrough in number and size sufficient to permit passage of sound-waves therethrough of appropriate volume without blurring, while at the same time preserving the light-reflecting properties of such surface sufficiently to 135 constitute an efficient screen for the presentation of the pictures, the walls of said openings being curved outer surfaces of threads of said fabric.

8. A moving-picture screen adapted for co-ordinated sound transmission, composed solely 140 of a single-thickness woven textile-fabric screen having a base of cotton and a front surface of silk, said silk having a front light-reflecting surface to receive the projected picture and said screen being provided with openings therethrough 145 in number and size sufficient to permit passage of sound-waves therethrough of appropriate volume without blurring, while at the same time preserving the light-reflecting properties of such surface sufficiently to constitute an efficient screen for 150

the presentation of the pictures, the walls of said openings being made up of rounded surfaces of said woven fabric.

9. A moving picture screen substantially impervious to light rays and having sufficient light reflecting properties to constitute an efficient projection screen adapted for co-ordinate sound

transmission comprising a single thickness of woven textile fabric having openings formed in the process of weaving said cloth and extending from front to rear of the screen sufficient in number and size to allow sound waves to pass through substantially unimpeded and undistorted.
